CLAIM

The ornamental design for a garden tractor, substantially as shown and described.

DESCRIPTION

FIG. 1 is a front and left side perspective view of a garden tractor showing our new design;

FIG. 2 is a side elevational view thereof taken from the side opposite that shown in FIG. 1;

FIG. 3 is a top plan view thereof;

FIG. 4 is a front elevational view thereof;

FIG. 5 is a rear elevational view thereof;

FIG. 6 is a front and left side perspective view of a second embodiment of a riding mower showing our new design, the sole difference being in the omission of the dual headlights.
